UNITED STATES PATENT OFFICE

ENOCH P. ESPING, OF YOUNGSTOWN, OHIO

DESIGN FOR A GAME TABLE

Application filed February 5, 1932. Serial No. 42,742. Term of patent 7 years.

To all whom it may concern:

Be it known that I, ENOCH P. ESPING, a citizen of the United States, residing at Youngstown, in the county of Mahoning and State of Ohio, have invented a new, original, and ornamental Design for Game Table, of which the following is a specification, reference being had to the accompanying drawings, forming part thereof.

I claim:

The ornamental design for a game table, as shown.

ENOCH P. ESPING.
